(57) **CLAIM**

The ornamental design for electronic cigarette case, as shown and described.

DESCRIPTION

FIG. 1 is a front, top and left side perspective view of the electronic cigarette case showing my new design; FIG. 2 is a rear, top and right side perspective view of FIG. 1; FIG. 3 is a front elevational view of FIG. 1; FIG. 4 is a rear elevational view of FIG. 1; FIG. 5 is a left side elevational view of FIG. 1; FIG. 6 is a right side elevational view of FIG. 1; FIG. 7 is a top plan view of FIG. 1; FIG. 8 is a bottom plan view of FIG. 1; FIG. 9 is a front, top and right side perspective view of FIG. 1 with a top cover thereof open; and, FIG. 10 is a rear, top, and right side perspective view of FIG. 1 with the top cover open.

The broken lines in FIG. 8 depict part of the electronic cigarette case and the broken lines in FIG. 9 depict environmental structure; All broken lines form no part of the claimed design.
